UNITED STATES PATENT OFFICE.

HENRY S. WING, OF ASHTABULA, OHIO, ASSIGNOR TO JENNIE A. WING, OF SAME PLACE.

CURTAIN-FIXTURE.

SPECIFICATION forming part of Letters Patent No. 252,851, dated January 24, 1882.

Application filed October 11, 1881. (No model.)

To all whom it may concern:

Be it known that I, HENRY S. WING, of Ashtabula, in the county of Ashtabula and State of Ohio, have invented certain new and useful 5 Improvements in Curtain-Fixtures; and I do hereby declare the following to be a full, clear, and exact description of the invention, such as will enable others skilled in the art to which it pertains to make and use the same.

10 My invention relates to an improvement in curtain-fixtures, the object being to provide an attachment for curtain-rollers which shall be cheap and simple in its construction and adapted to hold the roller in a fixed position by friction.

15 With these ends in view my invention consists in the combination of parts hereinafter described, and pointed out in the claims.

In the accompanying drawings, Figure 1 is 20 a view in perspective of my invention. Fig. 2 is a longitudinal section taken through a portion of the roller and the friction holding device, and Fig. 3 is a modification.

25 A represents a bracket provided with a flange, *a*, for its attachment to the window-easing by screws *b*. Bracket *A* is formed with a circular disk, *B*, and a cord eye or loop, *b'*, being made integral with the bracket, or being made separate therefrom and riveted or soldered thereto.

30 *C* represents the curtain-roller, one end thereof having a socket, *c*, formed therein, within which is inserted a spiral spring, *D*, the outer end of the spring bearing against the inner face, *d*, of the bracket.

35 *E* is a friction-disk, which may be made of any sheet metal desired, but is preferably formed of sheet-steel. Disk *E* may be made of any desired form—as, for instance, it may 40 be square, hexagonal, or star-shaped, as illustrated in the drawings. The points *e* of the friction-disk are slightly curved toward the outer face of the bracket and rest upon the outer edge of the bracket-disk *B*, whereby the 45 tension of the spring-arms of the disk may be utilized to the best advantage, as will herein-after appear. *F* is a shank formed of a rod secured at one end to the friction-disk and screw-threaded at its opposite end, whereby it may 50 be attached to the end of the roller.

Having described the construction and form of the several parts of my improvement, I will now briefly describe its operation.

The holding force of the curtain is regulated by adjusting the friction-disk *E*, which latter, 55 on being turned in one direction, has its spring-arms drawn against the bracket, thereby utilizing the tension of the arms of the disk in holding the roller in a stationary position and supporting the curtain in any desired adjustment. 60 The spiral spring inserted in the end of the roller tends to force the roller away from the bracket, and thus holds the friction-disk in snug engagement with the supporting-bracket.

65 By turning the friction-disk its tension may be regulated to uphold any size or weight of curtain.

Instead of employing a spiral spring within a socket in the curtain-roller, I may use a rubber block with a washer interposed between 70 the end of the roller and the inner face of the bracket.

The friction-disk may be corrugated; or it may be made cup-shaped, and provided with a serrated edge that bears against the supporting-bracket. 75

Instead of employing the form of bracket shown in the drawings, it may be made as shown in Fig. 3, and the same results secured.

Having fully described my invention, what 80 I claim as new, and desire to secure by Letters Patent, is—

1. In a curtain-fixture, the combination, with the roller and the screw-threaded shank, of the bracket through which the shank extends, a 85 spring, *D*, and disk *E*, the latter being secured to the end of the shank and adapted to bear against the outer side of the bracket, substantially as set forth.

2. In a curtain-fixture, the combination, with the roller having the socket *c*, of the screw-threaded shank *F*, disk *E*, secured thereto, the bracket *A*, and spring *D*, surrounding said shank within its socket, said disk *E* being adapted to have frictional engagement with 95 the disk *B* of the bracket, substantially as set forth.

In testimony whereof I have signed this specification in the presence of two subscribing witnesses.

HENRY S. WING.
